UNITED STATES PATENT OFFICE

118,694

DESIGN FOR A GAME BOARD

Robert H. Deaderick, Jacksonville, Fla.

Application November 20, 1939, Serial No. 88,379

Term of patent 7 years

To all whom it may concern:

Be it known that I, Robert H. Deaderick, a citizen of the United States, residing at Jacksonville, in the county of Duval and State of Florida, have invented a new, original, and ornamental Design for a Game Board, of which the following is a specification, reference being had to the accompanying drawing, forming part thereof.

I claim:

The ornamental design for a game board, as shown.

ROBERT H. DEADERICK.
